UNITED STATES PATENT OFFICE

127,484

DESIGN FOR A TROUSERS HANGER

Phillip A. Kilgore, Lynn, Mass.

Application July 24, 1940, Serial No. 93,911

Term of patent 14 years

To all whom it may concern:

Be it known that I, Phillip A. Kilgore, a citizen of the United States, residing at Lynn, in the county of Essex and State of Massachusetts, have invented a new, original, and ornamental Design for a Trousers Hanger, of which the following is a specification, reference being had to the accompanying drawing, forming part thereof.

I claim:

The ornamental design for a trousers hanger,
as shown.

PHILLIP A. KILGORE.
